Howard Brown

UNITED STATES PATENT OFFICE.

ELWOOD B. AYRES, OF PHILADELPHIA, PENNSYLVANIA, ASSIGNOR TO THE PHILADELPHIA TEXTILE MACHINERY COMPANY, OF PHILADELPHIA, PENNSYLVANIA, A CORPORATION OF PENNSYLVANIA.

DRYER.

1,255,686.

Specification of Letters Patent.

Patented Feb. 5, 1918.

Application filed March 16, 1917. Serial No. 155,286.

To all whom it may concern:

Be it known that I, Elwood B. AYRES, a citizen of the United States, residing in Philadelphia, Pennsylvania, have invented 5 certain improvements in Driers, of which the following is a specification.

My present invention relates to driers for bricks and similar material such as described in the pending application filed by me on 10 May 3, 1916, under Serial No. 95,078.

One object of my present invention is to provide means for introducing heated air to any one or all of the chambers and to provide means for circulating the air in the several chambers.

A further object of the invention is to provide means for introducing fresh air into the chambers independently of the heated air.

20 Fig. 1 is a plan view of a drier illustrating my invention;

Fig. 2 is a side view of the same;

Fig. 3 is a sectional view on the line 3-3, Fig. 2;

25 Fig. 4 is a sectional view showing one of the curtains.

By my invention I utilize the waste heat from a brick kiln by conveying the heated air from the kiln to the drier and admitting 30 it to any one or all of the three chambers of the drier.

Referring to the drawings, 1 is the casing of the drier, of any form desired, and it may have any number of sections. In the present 35 instance, I have shown the drier consisting of three sections *a*, *b*, and *c*. The several sections can be separated by movable curtains 2, which are adapted to rollers 3 and which can be raised to allow trucks to pass 40 from one section to another and to be lowered after the trucks are in position. In the present instance, there are three longitudinal tracks 4, which extend entirely through the drier and on these tracks are trucks 5 carrying the bricks. The bricks are piled on the 45 trucks in such a manner that air can circulate freely through the spaces between the bricks. At the forward end of the drier is a door 6 in the form of a curtain and at the discharge end of the drier is a door 7, also in the form of a curtain. 8 is a series of circulating fans located in the upper portion 50 of the drier, and, in the present instance, there are two fans in each compartment *a*, *b*, and *c*. Each of these fans is mounted on a

vertical shaft, 9 having its bearings in the frame of the drier structure and at the upper end of each shaft 9 is a bevel wheel 10 meshing with a bevel wheel 11 on a longitudinal shaft 12 in any suitable manner. 13 is a flue 60 communicating with the kiln through which the waste heat is conducted to the drier. Hot air from a kiln is forced through the flue 13 by any suitable fan or blower, as in the application hereinbefore referred to, and 65 the hot air can enter the last section *c*. In the passage 14 is a damper 16 and in the passage 15 is a regulating damper 17 and connecting with the passage 14 is a fresh air flue 18 having a damper 19 so that by regulating 70 the dampers 16, 17 and 19, the proper amount of heated air and fresh air can be discharged into the last section *c* and the air, as it circulates in this section, is carried to the opposite end of the section and down through the 75 connecting flue 20 to one end of the section *b*. A damper 21 regulates the flow of air through this flue and connecting the forward end of the section *b* with the rear end of the section *a* is a flue 22 in which is a damper 80 23 so that the air admitted to one end of the section *c* can circulate through said section and through the sections *b* and *a* and finally discharge through an exhaust flue 24 communicating with the forward end of the section *a*. Communicating with the flue 13 is a flue 25 having a damper 26 and this flue 85 communicates with the rear end of the section *b* through a duct 27 in which is a damper 28 and also through a duct 29 with the rear end of the section *a* and in the flue 25 at this point is a damper 30. By this arrangement a certain amount of hot air can be carried directly to the section *a* or to the section *b* and mixed with the air passing 90 from one of the other sections or by adjusting the dampers 21 and 23 and opening the dampers 26, 28 and 30 the air can circulate independently in each of the sections.

The waste heat from the kiln is usually 100 discharged from the kiln at about 500 degrees F., and the temperature may be reduced by the admission of fresh air through the duct or flue 18 to about 800 degrees F., or much lower, and by regulating the dampers 105 the proper degree of heat can be maintained in the several sections of the drier. The dampers are preferably controlled by automatic damper regulators which may be of any of the common types.

By this construction, the air passes from the discharge end of the drier toward the forward end, consequently, the moisture in the air is greater at the section where the 5 bricks are admitted to the drier than at the point where they are discharged therefrom, consequently, the bricks are subjected to the moist, heated air in the first section of the drier and to heated air of a less degree in 10 the second section, so that the moisture is held in the bricks to prevent the bricks from drying on the outside before the interior is thoroughly dried. When the bricks pass into the third chamber they are subjected 15 to dry heat which completes the drying of the bricks so that when they are delivered at the discharge end of the drier they are thoroughly dried.

I preferably extend the fresh air duct or 20 flue 18 at the side of the drier, as shown at 31, and connect it with the sections *a* and *b* through ducts 32 and 33 respectively, each having a damper therein. By this means, 25 the temperature in the several sections can be reduced, if found desirable.

I claim:

1. The combination in a drier, of a series of compartments, each compartment having a drying chamber; means for supporting the 30 material to be dried in said chambers; flues for conducting hot air to the several chambers; flues connecting the several chambers; and an exhaust flue communicating with one of said chambers so as to exhaust the moist 35 air from said chamber.

2. The combination in a drier, of a series of compartments, each compartment having a drying chamber; means for supporting the material to be dried in the several chambers; 40 movable curtains dividing the chambers so that material can be transferred from one chamber to another; a flue for hot gases communicating with the last of the series of chambers; flues connecting the several chambers; and an exhaust flue communicating 45 with the first chamber so that the air, as it passes from one chamber to another, will collect the moisture and will be finally discharged from the chamber into which the 50 material to be dried is first entered.

3. The combination in a brick drier, of a series of compartments; curtains separating the compartments; tracks extending through the compartments so that cars carrying the bricks can be moved from one compartment 55 to another; a flue for heated air communicating with each of said compartments; dampers for cutting off any one of the compartments; flues forming communication between two adjoining compartments; a damper in each flue; and an exhaust flue communicating with the first compartment to remove moist air from said compartment.

4. The combination in a brick kiln, of a series of compartments; a track extending 65 through the kiln so as to allow trucks on which the bricks are mounted to be transferred from one compartment to another during the drying process; means for circulating air in each of said compartments; 70 a flue for conducting hot air and communicating with the several compartments; dampers for regulating the passage of the air to the several compartments; a flue for admitting fresh air to the first compartment; flues connecting 75 one compartment with another; a damper in each flue; and an exhaust flue for the discharge of moist air in the first compartment so that the air in the first compartment will be moist while the air in the last 80 compartment will be dry in order that the moisture may be held in the bricks of the first compartment to prevent the bricks from drying on the outside before the interior is thoroughly dried, while the bricks in the 85 last compartment are subjected to dry heat which completes the drying of the bricks.

5. The combination in a drier, of a series of compartments, each compartment having a drying chamber; means for supporting 90 the material to be dried in said drying chambers; flues for conducting hot air to the several chambers and flues for conducting fresh air to the said chambers; flues connecting the several chambers; dampers in said flues; 95 and means for exhausting the moist air from one of said chambers.

In witness whereof I affix my signature.

ELWOOD B. AYRES.
